UNITED STATES PATENT OFFICE.

WILLIAM D. LIPPS, OF FREDERICK, MARYLAND, ASSIGNOR TO OX FIBRE BRUSH COMPANY, OF NEW YORK, N. Y., A CORPORATION OF WEST VIRGINIA.

BRUSH MACHINE.

Application filed November 15, 1923. Serial No. 674,794.

This invention relates to brush machines, and particularly machines of the type illustrated in the Young Patents Nos. 578,907 and 664,989, dated March 16, 1897, and 5 January 1, 1901, respectively, wherein brush blocks are bored, and wisps of fibre or bristles are successively removed from a magazine and transferred to a station where each succeeding wisp is doubled on itself, 10 seated in a hole of a brush block, and therein fastened by means of a wire staple that is formed by the machine.

The object of my invention is to improve machines of the type referred to in various 15 particulars hereinafter pointed out, whereby, amongst other important results, a more rapid and economical operation of the machine than formerly, with correspondingly increased capacity, is attained.

20 The invention comprises various novel principles of operation, features of construction and combinations of parts, all of which will be hereinafter described, and the precise scope of the invention then be defined 25 in the appended claims.

In the drawings—

Figure 1 is a side elevation of a brush machine embodying my invention.

Fig. 2 is a partial rear elevation of the 30 machine.

Fig. 3 is a longitudinal vertical section of the machine, as on the line 3—3 of Fig. 2.

Fig. 4 is a similar section, as on the line 4—4 of Fig. 2.

35 Fig. 5 is a sectional elevation of the mechanism for intermittently and continuously actuating the pattern wheels.

Fig. 6 is a sectional elevation, enlarged, 40 of a portion of the cam shaft, its pulley, cams, clutch and brake devices, and adjuncts.

Fig. 7 is a transverse vertical section through the shaft, as on the line 7—7 of Fig. 6.

Fig. 8 is a view of the toggle mechanism 45 and connections for actuating and controlling the clutch and brake devices between the said pulley and the adjacent cam element on the cam shaft, the position of the toggle mechanism when the said cam element is idle being indicated by dotted lines.

Fig. 9 is a vertical section through the pattern wheels, the driving gear therefor, and adjuncts.

Fig. 10 is a horizontal section through 50 the fibre magazine and the adjacent part

of the supporting frame, showing the fibre gathering mechanism and associated parts, the tuft casing and its appurtenances being omitted for clearness.

Fig. 11 is a transverse vertical section, as 60 on the line 11—11 of Fig. 10.

Fig. 12 is an elevation of the mechanism shown in Fig. 10, as viewed from the right hand side, the fibre gathering devices being 65 illustrated in their rearward stroke.

Fig. 13 is a similar view showing the fibre gathering devices at the limit of their forward stroke, and the wisp of fibre as transferred to the removing and retaining devices at the inserting station. In this view 70 the tuft casing is illustrated in section in its vertical position to receive the tuft and guide it to the underlying brush block.

Fig. 14 is an elevation of one side of the magazine, showing its vibratory fibre even- 75 ing wall and the actuating devices therefor.

Fig. 15 is a horizontal section through the lower part of the magazine, as on the line 15—15 of Fig. 14.

Fig. 16 is a vertical section, as on the line 80 16—16 of Fig. 14.

Fig. 17 is a detail, in perspective, of a compressor block which bears upon the fibre gathering bar at the rear of the magazine.

Fig. 18 is a front elevation of the vertically reciprocative tuft inserting and fastening slide and adjuncts, showing the staple bending anvil in section, with a staple formed thereon and seated in and between the jaws of the slide, and showing also the 90 tuft positioned below the slide.

Fig. 19 is a similar view, showing the slide in down position with its jaws and the staple embracing the tuft preparatory to the act of driving the staple into the hole of the 95 brush block.

Fig. 20 is a horizontal section through the slide, and the guide therefor, as on the line 20—20 of Fig. 18.

Fig. 21 is a section of a part of a brush 100 block showing the tuft as fastened thereto by the staple.

Fig. 22 is a front elevation of the oscillatory tuft casing, and the slide, link and gear connections for operating the same, the 105 parts being shown in the relative positions they occupy when the casing is in vertical or tuft receiving position.

Fig. 23 is a transverse vertical section, as 110 on the line 23—23 of Fig. 22.

Fig. 24 is a transverse horizontal section, as on the line 24—24 of Fig. 22.

Referring to the drawings, 1 designates the supporting frame; 2 the drive shaft of the machine, and 3 an upper transverse shaft on which is loosely mounted a pulley 4 that is connected with and continuously driven from a pulley 5 on the drive shaft by means of a belt 6.

7 designates a third shaft which is intermittently and continuously rotated as will presently appear. Fast on the shaft 7 are spaced-apart wheels 8, 8 to which are affixed appropriate segmental pattern cams 9 that determine the succeeding movements of the mechanism for controlling the various positions of the block-supporting table 10 in the usual manner.

11 designates a fourth shaft which is driven from the shaft 2 by means of a belt 12 passing about pulleys 13, 14 on the shafts 2, 11, respectively. On the shaft 11 is a pulley 15 which is operatively connected with the pulley 16 of the drill head by means of a belt 17 so as to continuously rotate the drill, which drill is mounted for vertical movement toward and from the path of the block-supporting table. The periodical vertical movements of the drill in respect to the block (B) on the table 10, so as to bore tuft-receiving holes in the block, is effected by means of a rock-lever 18 which is fulcrumed on the supporting frame, one of the arms of the lever being coupled to the movable drill support, and the other arm having a roll connection, as usual, with an appropriate cam 19 fast on the shaft 3.

20 designates the magazine from which quantities of fibre, or bristles, are successively removed and fed into position for insertion, as tufts, into the holes of the adjacent bored block (B) on the table 10. The tuft inserting mechanism includes devices whereby each tuft is seated and fastened in a hole in the block by means of a wire staple, which staple when driven toward and into the hole of the block straddles the wisp, doubles the wisp on itself, carries the tuft thus formed into the hole, and securely fastens it therein.

On the shaft 7 is a relatively large gear wheel 21 with which meshes a smaller gear wheel 22 carried by a shaft 23 journaled in suitable bearings on the main frame. The shaft 23 bears a ratchet wheel 24 the teeth of which are engaged by a pawl 25 on one arm of a crank lever 26 that is fulcrumed on the shaft 23. The other arm of the lever is connected by means of a link 27 with one arm of a crank lever 28 that is fulcrumed on the frame adjacent the shaft 3. The other arm of the latter lever is provided with a roll 29 that runs on an appropriate cam 30 that is mounted on the shaft 3. Means, including manually operable devices, are provided

whereby the cam can be coupled at will to the continuously driven pulley 4 so as to turn therewith, and including, also, devices whereby the cam is automatically released at predetermined intervals, as will hereinafter appear. The roll is maintained in operative contact with the cam 30 by means of a spring 31 suitably secured to the crank lever 28 and to the frame, and the contour of the cam is such that when the cam is in operative connection with the pulley 4 the lever 28 is actuated in a manner to oscillate the pawl bearing lever 26 and effect by its pawl the uniform intermittent rotation of the associated ratchet and gear wheels, which motion is transmitted to the gear wheel 21 and, perforce, to the shaft 7 and its pattern cam wheels.

In the present instance the cam 30 comprises an eccentric disk formed with an elongated sleeve or hub 32 which loosely encircles the shaft 3. This sleeve is provided at the end adjacent the pulley 4, with a brake drum 33 upon one face of which is pivoted a clutch lever 34, the shorter arm whereof terminates in a head 35 that, by actuation of the lever, is movable into and from the path of a laterally projecting stud 36 on the pulley. When the lever head is in the path of the stud, the latter bears against the head and thereby rotates the sleeve and cam concurrently with the pulley, but when the lever head is withdrawn from such path the pulley rotates idly and the sleeve and cam are quiescent. The clutch lever is held normally in stud engaging position by the pressure against its longer arm of a spring 37 which is supported by a suitably-disposed stem 38 mounted on the side of the brake drum. The brake drum 33 is embraced by a pair of pivoted brake members 39 terminating in parallel jaws 40 that are connected by a spring-pressed rod 41 which tends to maintain the said members in clamping relation with the brake drum. These members are supported by an arm 42 pivoted to a bracket 43 on an adjacent part of the main frame. (See Figs. 6 and 7.)

Interposed between the brake jaws is a cam 44 fast on a rocker-shaft 45 having its bearing in a bracket on the main frame. On one end of this shaft is secured an arm 46 having at its free end a roll 47, which, when the shaft is properly actuated at predetermined periods by manually operative and automatic controlling mechanisms, such as hereinabove described, to release the brake members from the drum in one period and to apply them thereto in another period, is moved respectively out of and into the path of the longer arm of the lever 34 as the drum rotates. By the operation of the manual control the roll is lowered and, in consequence, the lever arm escapes the roll and is maintained in the path of the pulley stud

36 by the action of the spring 37; the brake at the same time being released to permit the free rotation of the cam element with the pulley. By the operation of the automatic 5 control the roll is raised into the path of the lever arm and, in consequence, such arm abuts against the roll and is thereby held with its head beyond the path of the pulley stud; the brake at the same time being applied 10 to the drum to prevent the cam element from drifting beyond the proper stopping and starting point. The control mechanisms just referred to are of the following construction, reference being had to 15 Figs. 2, 3, 4, 6, 7, 8 and 9 of the drawings.

Fast on the shaft 45 is an arm 48 to which and to the main frame are jointed the respective members of a toggle 49 which is maintained in its straight or open position 20 and against a suitably-disposed stop 50 on the frame, by means of a spring 51 secured to one of said members and to the frame. When the toggle is in this position the arm 46 is maintained with its roll 47 in the path 25 of the depending arm of the clutch lever 34 and the rocker-cam 44 in position with the brake applied. On the lower member of the toggle is a laterally projecting roll 52 against which bears an oscillatory cam lever 30 53 which is fast on a stud-shaft 54 journaled in a suitable bearing in the frame. The longer arm of the lever 53 constitutes the cam member, and the shorter arm is connected by means of a link 540 with an arm 550 35 fast on one end of a rocker-shaft 560 having its bearing in the bracket 570. The free end of the shaft 560 is equipped with a handle 580 which, when it is turned to the right or to the left, turns the shaft and its arm in a 40 manner to depress the link 540 and swing the cam arm of the lever 53 forcibly upward against the roll 52 of the toggle, thereby pushing the toggle outward beyond the vertical and against the action of the spring 45 51, and perform drawing down the arm 48 and partially turning the rocker-shaft 45. Consequently the roll 47 of the arm 46 is removed from the path of the depending arm of the clutch lever 34, the head of the 50 latter is caused to assume its position in the path of the pulley stud 36, and the brake is released from the brake drum; whereupon motion is transmitted from the pulley to the cam element 30.

55 The toggle is locked in its outwardly swung position, in opposition to the force of the spring 51, by means of a suitable locking device, which, in the present instance, comprises an arm 590 which is hung on the shaft 54 laterally of the cam lever 53 and is formed with a notched outer end portion 600. The cam lever is provided with lower and upper lugs 610, 620 which respectively underlie and overhang the body of the locking arm, 60 the relation of the parts being such that

when the cam lever is being raised and the toggle swung outward as above described, the underlying lug 610 lifts the arm 590 into a position to engage its notched end with the toggle roll 52 and thus hold the toggle projected, and that when the cam lever is swung downward through the instrumentality of the automatic devices now to be described the upper lug 620 forces the locking arm downward and away from the roll in a manner to release the toggle and permit the spring 51 to return it to its straight position; thus interrupting the connection between the pulley and the cam element, applying the brake and stopping the rotation 75 of the cam element.

Projecting from the shaft 54 is an arm 630 which is connected by means of a link 640 with a crank-arm 650 fixed on a rock-shaft 660 located laterally adjacent the gear 80 wheel 21. On this shaft is also fixed an arm 670 provided with a cam head 680 which lies normally in the path of a laterally projecting stud 690 on the gear wheel. This stud at a predetermined interval in the rotation of the gear wheel impinges against the cam head and swings the rock shaft and the arm 650 in a manner to raise the link 640 and the arm 630, thus lowering the cam arm 53 and causing the upper lug 620 to impinge against the locking arm 590 and effect the release of the toggle as and for the purpose previously explained.

On the shaft 3, adjacent the cam 30, is secured a brake drum 330, on one side of which is pivoted a clutch lever 340 generally similar to the lever 34 hereinbefore described. The head of the lever 340 is provided with a tooth 350 which by actuation of the lever is movable into and from engagement with a notch in a head 360 fixed on the adjacent end of the cam hub or sleeve 32, and the brake drum 330 is provided with brake-members 390 which are operable by a rocker cam 440 similar to the rocker cam 44. The shaft 450 of the cam 440 has its bearing in a bracket 571 and is provided with an arm 460 having at its outer end a roll 470 which, coincidentally with the operation of the shaft to apply the brake members to the drum 330, is moved into position to actuate the clutch lever 340 and disengage its tooth from the notched head 360.

When the clutch lever is engaged with the notched head, the motion is transmitted to the shaft 3 and its fixed cams from the cam sleeve 32, but when the lever is disengaged from the head the motion of the shaft is at once stopped. The rocker-shaft 450 is automatically operated at predetermined intervals to engage and disengage the lever with and from the clutch head respectively. Accordingly the shaft is equipped with an arm 480 which is connected by means of a rod 681 with one arm of a crank lever 691 ful-

crummed on a bracket adjacent the gear wheel 21. The other arm of this crank lever is provided with a roll that is maintained normally in the path of a suitably disposed 5 cam 700 on the gear wheel 21 by the action of the spring and cam connections of the brake.

The co-operative relation of the parts just described is such that when the crank lever 10 691 is in the normal position, the clutch lever 340 is disengaged from the clutch head 360 and the brake members 390 grip and hold the brake drum 330; but when such crank lever is engaged by the cam 700 the lever 15 is moved against the force of the brake spring in a manner to effect a partial turn of the rocker-cam 440, thereby moving the roll 470 into the path of the clutch lever 340 and effecting the engagement of the 20 latter with the clutch head, and also coincidentally releasing the brake-members from the drum 330.

On the shaft 3 are secured, in addition to the cam 19 which operates the boring devices, 25 the cam elements for operating the fibre gathering and the tuft inserting and fastening mechanisms, and hence by virtue of the described mechanism for automatically controlling the active and idle periods of the 30 shaft, while the pattern wheels are in operation, there can be accomplished the automatic filling of a brush block in which the spaces between adjacent holes exceed the throw imparted to the block by a single 35 intermittent movement of the pattern wheels. That is to say, if it be desired to fill two ends, for example, of a brush block, leaving the center plain, the cam 700 on the gear wheel 21 is so formed and disposed as to effect the 40 release of the clutch lever 340 from the clutch head and, coincidentally, apply the brake to the drum 330, for a predetermined interval during which the cam 30 is continuously driven from the pulley 4 until the 45 block has been intermittently advanced a number of steps comprising its plain surface, and then to effect the re-engagement of the clutch lever 340 and the release of the 50 associated brake preparatory to the resumption of the boring and filling operations on the other end of the block. Upon the completion 55 of the brush the clutch lever 34 and its associated brake are actuated through the stud 690 and connections hereinbefore described in a manner to disconnect the cam 30 from the pulley 4 and apply the brake to the drum 33; thus stopping the operation not only of the pattern mechanism but also of the 60 boring and filling mechanisms. To resume the operation it is merely necessary to turn the handle 580 of the rocker-shaft as previously explained.

It will also be seen that by the described 65 control mechanisms the continuous boring and filling of more than one block at a time

may be accomplished, (by using a multiple table) since the cam 700 can be so formed and positioned as to render the shaft 3 and its cams idle during the time that the pattern mechanism which is under the influence of the active cam 30 is moving one block from and another block into operating position in respect to the boring and filling devices. Furthermore by the described control mechanisms may be produced numerous brush 75 patterns wherein the spaces between adjacent tufts or groups of tufts exceed the normal intermittent movement of the block during a single cycle of the boring and filling operations.

As a simple and efficient means whereby the velocity of the shaft 7 and the pattern wheels, can be accelerated, during such periods of the operating cycle that the boring and filling mechanisms are idle, thus increasing the output and efficiency of the machine, I provide automatic rapid speed mechanism of the following description, reference being had to Figures 1, 2, 3, 4 and 5 of the drawings.

Journalized in suitably disposed bearings is a shaft 710 having a tight pulley 720 which is connected with and driven from a tight pulley 730 on the shaft 2 by means of a belt 740. Adjacent the pulley 720 is pivotally supported the lower end of an upstanding rock frame 750 in the upper end of which are mounted parallel shafts 760, 770 bearing meshing gear wheels 780, 790, respectively. Fast on the shaft 760 is a pulley 800 which is connected with and driven from a tight pulley 810 on the shaft 710 by means of a belt 820, and hence the motion is transmitted to the gear wheels 780, 790. The latter wheel is so disposed that by actuation of the rock frame, said wheel 790 may be moved into or out of mesh with a gear wheel 830 tight on the shaft 23 that bears the gear 22 and ratchet wheel 24. A spring 840 secured to the rock-frame and to the main frame tends to maintain the former positioned with the gear wheel 790 in mesh with the gear 830, and therefore the motion is transmitted through the gear 830 to the shaft 23 and thence through the gear 22 to the gear 21 on the pattern wheel shaft 7. As the movement thus imparted to the shaft 7 is continuous and at a higher speed than that transmitted intermittently thereto through the ratchet wheel 24, the velocity of the shaft 7 and its pattern wheels is accelerated, thus correspondingly increasing the periodic movement of the work carrying table. Consequently the inoperative interval of the boring and filling mechanisms, necessitated by gaps in the brush pattern, or by jumps from one block to another (when operating with a multiple table), is reduced, resulting in increased output.

Mounted on the gear shaft 770 is a roller 130

850 which at predetermined intervals is engaged by a suitably-disposed cam 860 on the gear wheel 21, and is thereby forced outward in a manner to swing the frame 750 5 against the force of the spring 840 sufficiently to throw the gear wheel 790 out of mesh with the gear 830. Thereupon the shaft 7 is intermittently operated through the ratchet wheel as previously described, 10 until such time as the gear 790 is permitted to resume its engagement with the gear 830. The gear 790 can be thrown into or out of operation at any predetermined point or points or for any desired period or 15 periods of the operating cycle, by the proper attachment of one or more cams, as 860, to the gear wheel 21.

The fibre magazine herein illustrated comprises a vertically-disposed U-structure 20 53' projecting from and secured to a vertical shaft 54' suitably supported by the frame; spaced parallel side walls 55 borne by the sides of said structure, and a back wall 56, which latter wall is affixed to 25 brackets 57 that are adjustably secured in place by set screws 58 passing through slots 59 in said sides as usual. The open bottom of the magazine overhangs an oscillatory fibre gathering device by means of which 30 quantities of fibre are successively separated from the mass in the magazine and fed into position for insertion, as tufts, into the adjacent bored block (B) on the table 10. This device, in its preferred form, 35 comprises a segmental bar 60 having in its upper edge a gap 61 so located that during the oscillation of the bar the gap is moved under and away from the bottom of the magazine, in a manner to receive and withdraw therefrom a sufficient quantity of fibre. A 40 notched regulator arm 62 disposed laterally of the gap is adjustable up or down to decrease or increase, as desired, the depth of the gap, and thus afford a simple and 45 efficient means to regulate the amount of fibre collected. The arm is provided at its ends with set-screws 63 which extend through elongated slots in the bar 60 and serve to secure the arm in any predetermined 50 position of vertical adjustment.

The segmental fibre gathering bar 60 is supported by the arms of a carrier 64 which is mounted for oscillation on the vertical shaft 54'. The carrier is connected by 55 means of a rod 65 with one arm 66 of a bell-crank lever fulcrumed on a frame extension at 67. The other arm of the lever bears a roll 68 which runs in the race of an appropriate face cam 69 fast on the 60 shaft 3; the contour of the cam race being such as to effect through the lever and link connections variable backward and forward motions of the carrier and its fibre gathering bar for a purpose hereinafter described. 65 Beneath the carrier is an arm 70 which is

also mounted to oscillate on the shaft 54'. This arm 70 extends outwardly under the segmental bar and carries at its outer end a pair of spaced segmental plates 71 which are shaped to embrace the bar and extend 79 to the top of the latter. The plates are fixed to the arm by screws 70', and are also slidably connected with the tuft bar by screws 72' passing through a slot 71' in the bar. The forward or acting ends of the 75 plates 71 are reduced and beveled to form clamping points, as 72, which, by the relative rotary movement of the plates and bar, can be caused to overhang and recede from the wisp of fibre supported in the gap, thus 80 respectively clamping and releasing the fibre. Fast on the arm 70 is a depending block or projection 73, constituting a bumper, into the path of which projects two spaced apart stops 74, 75 fast on an 85 arcuate frame extension 76 located below the carrier, whereby during the oscillation of the arm the bumper engages the stops in alternation. (See Figs. 1 and 10 to 13, 90 inclusive).

Mounted in guide brackets 77 on the underside of the arm 70 is a radially-movable bolt 78 which is maintained normally projected outwardly by means of a suitably-disposed spring 79 confined in one of the 95 brackets. The outer end of the bolt is V-shaped, as at 80, and its inclined faces engage one side or the other of a stud 81 that depends from the carrier through an arcuate slot 82 in the arm. The bolt connection is such that during the forward stroke of the carrier the bolt is positioned to bear against the rear of the stud, and hence the arm is moved forward by and with the carrier until the bumper 73 impinges against the 100 opposing stop 74. Thereupon the forward motion of the arm is stopped and, in consequence, as the carrier continues its stroke, the spring bolt is forced inward and released from the stud. In the return stroke of the 105 carrier the bolt impinges against the front of the stud and forces the arm rearward with the carrier until the bumper impinges against the rear stop 75, whereupon the rearward motion of the arm is stopped, and, as the 110 stroke of the carrier continues, the bolt is forced inward and released from the stud.

The contour of the race of cam 69 is such that strokes of varying extent are imparted thereby through the connecting rod 65 to the oscillatory fibre carrier in such a manner as to give the gap of the bar several opportunities to be filled with fibres from the magazine; that is to say, the carrier is first given a backward stroke from the tuft inserting station until the gap of the tuft bar passes beneath the magazine and reaches the rearward wall of the latter; then the carrier is given a partial forward stroke to advance the gap to the forward wall of the magazine; 125 130

then the carrier is given a rearward stroke to move the gap beyond the rear wall of the magazine; then, finally, the carrier is given a full forward stroke to advance the gap to the tuft inserting station. In each of the movements of the gap beneath the magazine, excepting the final forward movement, such gap is given an opportunity to be filled with fibre. In its final movement rearward of the magazine the bumper 73 abuts against the stop 75 and thus shifts the segment plates 71 in a manner to advance the points 72 thereof into clamping relation to the gap and thereby confine the contained wisp of fibre. In the next succeeding forward motion of the carrier beyond the magazine the bumper 73 impinges against the stop 74 which effects the opening of the clamping points in a manner to release the fibre, at which juncture the fibre is located beneath the tuft inserting mechanism hereinafter described, and is removed from the gap and supported by novel clamping devices. Such devices, in their preferred form, comprises a pair of parallel arms 83 secured to a support 84 on the main frame and having a pair of overhanging hook members 85 which are disposed in spaced relation to the respective sides of the segmental tuft bar so as to lie adjacent the path of the wisp of fibre as it is being advanced to the inserting station. Adjacent the outer sides of the respective members are a pair of fingers 87 which extend from a rock shaft 89 having its bearings in brackets 90 on the support 84, the free ends of said fingers being shaped to afford notches 91 adjacent the respective hook members 85. Encircling the shaft is a spring 88, one end of which is secured to the shaft and the other end to a bracket 90, such spring thus tending to maintain the shaft normally in a position with the fingers upwardly inclined and their notches 91 above the plane of the tuft bar. The fingers are temporarily held in down position by a cam piece 92' on the underside of one arm 92 of a latch lever which is pivoted to the frame, as at 93, said cam piece by the actuation of the lever being movable upon and from the adjacent finger. The arm 92 is maintained yieldingly in outer active position, with the cam piece overlying the finger, by means of a stout retracting spring 94 attached at its respective ends to the lever and to the frame. The other arm 95 of the latch lever extends into the path of a lug member 96 adjustably fixed on the connecting rod 65 in such spaced relation to the arm 95 that the lug 96 impinges against and swings the arm in opposition to the spring 94, so as to remove the cam piece from the underlying finger at the moment the gap 61 of the tuft bar, with its contained wisp of fibre, is positioned under the hook members 85; whereupon the fingers, rising, lift the fibre from the gap 61 into the hook por-

tions and hold it securely therein in proper position for engagement by the tuft inserting mechanism. In the downward or active stroke of the said mechanism the fingers are depressed, and by the retraction of the lug member on the rod, such fingers are subsequently locked by the cam piece of the latch lever in the open position in readiness to engage and lift the next succeeding wisp of fibre advanced by the fibre gathering bar. (See Figs. 10, 12 and 13).

It is to be noted that when the carrier progresses nearly to the extreme forward position the bumper 73 is held against the stop 74, which arrests the further forward movement of the arm 70 and its segments 71, including the clamping points 72, while the carrier and its fibre gathering bar continue to the end of the stroke as determined by the movement of the connecting rod 65 through its actuation by the cam 69, such continued travel causing the gap 61 to move clear of the clamping points. Thereupon the bar is locked by the engagement of the bolt with the stud 81, such bar then being in position to discharge the fibre into the hook members 85 as previously mentioned. The carrier then reverses its direction of travel, and the arm 70 with its open clamping plates are carried thereby. When the gathering bar is positioned with its gap under the magazine (the upper edge of the bar being at all times in contact with the fibre in the magazine), the gap is supplied with the overhanging fibre. The additional forward and backward movements of the bar carry the gap across the width of the magazine, thus insuring the descent of an adequate quantity of fibre to fill the gap, as previously explained. On the second backward movement the travel of the arm 70 and the clamping points is arrested by the abutment of the bumper 73 against the stop 75, while the carrier continues a distance sufficient to move the gap 61 of the bar under the said points and to cause the beveled end of the locking bolt 78 to pass to the opposite side of the stud 81 and lock the clamping points upon the wisp of fibre in the gap until it is carried to the clamping device beneath the tuft inserting mechanism.

Secured to the lower portion of the rear wall of the magazine frame is a bracket in which is slidably mounted the vertical stem 97 of a compression block 98 that overhangs the fibre gathering bar. Within the bracket is a suitable spring 99 that tends to depress the block and maintain it in sliding contact with the top of the bar. This block comprises a body member having on its lower face a central rib 100 that rests on and longitudinally of the top of the bar and two laterally depending ribs 101, the lower forward ends of which latter are beveled or inclined, as at 102. The position of the block is such

- that in the final backward movement of the gathering bar, after the gap of the latter has been supplied with fibre, such fibre is passed beneath the ribs of the block before the 5 clamping points are brought into operation, and in consequence the fibre is uniformly depressed beyond both sides of its median portion by means of the lateral walls. (See Figs. 14 to 17, inclusive.)
- 10 From the foregoing described construction and operation of the relatively movable fibre carrying and clamping members, it will be seen that the tuft of fibre is gripped midway between its ends and that, therefore, 15 a uniform pull is exerted on the wisp when it is being separated from the contents of the magazine, thus preventing dragging and displacement of the fibres of the wisp and insuring a uniform collection and disposition 20 thereof; second, that by the provision of means for controlling the movement of the locking points of the relatively movable members it is possible to pass the fibre gatherer back and forth beneath the magazine as often as is necessary to insure the 25 adequate filling of the fibre receiving gap; and, third, by the agency of the compressor block in conjunction with the final rearward impulse of the gathering bar to bring the fibre under the block before the clamping points are brought into operation, the wisp of fibre is well pressed into the gap of the bar and the efficient action of the double clamping points on the fibre is ensured. 30 Hence there is an efficient retention of all the fibres in the gap of the bar during the transfer of the wisp to the inserting station, resulting in a saving of fibre and in the production of a uniformly filled brush. 35
- 40 As a simple and efficient means to even the fibres in the magazine, I hinge to a suitably disposed support 102' below the magazine, the lower end of a vertical plate 103 which lies adjacent the open outer side of the magazine and is adapted to be laterally vibrated in a manner to press intermittently against the outer ends of the contained fibres. This plate is connected, by a pin and hook for example, to the longer arm of a horizontal lever 104 which is fulcrumed on a pivoted arm 105 depending from the magazine frame, the shorter arm of the lever terminating in a toe 106 which extends into the path of a tappet 106' secured to the hub of the carrier, so that as the carrier approaches the end of its backward stroke the tappet impinges against the toe and thereby slightly pulls the lever and therewith the plate 103 in a manner to press the latter squarely against the ends of the fibres contained in the magazine. When the carrier recedes the plate resumes its normal position in readiness for a succeeding impact upon the return of the carrier. (See Figs. 10, 14 and 15.) 55
- 60 When the wisp of fibres is presented to the tuft-inserting station the wisp is seated and fastened in a hole in the brush block by means of a wire staple which when driven toward and into the hole of the brush block straddles the wisp, doubles the wisp on itself, 70 carries the thus formed tuft into the hole, and securely fastens it therein. The tuft fastening devices are generally of the character described in patent No. 746,943, dated December 15, 1903, excepting in respect of the 75 staple guide and ancillary actuating devices therefor, which are of such construction that the depending legs of the staple confined in the guide are bent into converging relation so that not only are the fibres well spread to 80 fill the hole in the brush block but a reliable bond is effected with the brush block, as will now be described.
- 85 Referring to Figs. 1, 3 and 18 to 21, inclusive, 107 designates a vertically reciprocative bar slidably fitted in a suitable guide-way 108 in the supporting frame. On the outer face of this bar is a cap plate 109 between which and the bar is supported a vertical slide comprising two spaced-apart 90 vertical members 110 having a pair of internally-grooved staple and tuft receiving jaws at its lower end. These members are pivoted at their upper ends to the cap plate 109 by means of screw studs 111 extending through vertical slots 112 in the plate, and are thus relatively movable toward and from each other, on their pivotal supports, in a manner to permit the closing or the opening 95 of the jaws at the lower ends of the members. The legs of a spring 113, which is coiled on the pivot stud of one member, bear respectively against the under side of the stud 111 of the other member and against a stud 114 100 projecting from the former member through a slot 115 in the cap plate. Pivoted to the lower portion of the cap plate is an outwardly and upwardly inclined arm 116 having at its lower end a cam portion 117 which bears against a movable pressure shoe 110' 105 located along the edge of the proximate member 110, said arm also having at its upper end a roll 118 so positioned that during the vertical reciprocation of the plate, the roll contacts with the inclined face of a 110 vertically disposed cam bar 119 fastened to the main frame. The contour of the cam face is such that in the downward stroke of the cap plate the arm 116 is swung inward, thereby turning the cam forcibly against the shoe 110' and pressing it, together with the opposing member 110, toward the other member in opposition to the force of the spring 113; and that in the upward stroke 115 of the cap plate, the arm 116 and its connections, resume their normal positions. The stud of the roll 118 extends through and is guided in an arcuate slot 120 in the upper end of an adjustable supporting arm 121 120 which is pivoted to the plate 109 co-axially 130

with the cam arm. The arm 121 is provided with an extension 122 which is adjustably secured to the plate by a screw 123 extending through a suitable arcuate slot 124 in the extension. The members 110 are resiliently connected to the bar 107 so as to have independent vertical movement thereon, by means of compression springs 125 which, being supported in a block 126 on the bar, bear upon the tops of the respective members. The studs 111 and slots 112 determine the relative vertical movements of said members and bar.

The adjacent inner edges of the two members 110 of the slide are longitudinally grooved to receive a staple driving bar 127 which depends from a slide 128 fitted in the guide way 108 of the frame, said latter slide, together with the bar 127, being relatively reciprocated vertically in the usual manner, as follows: The upper end of the slide is connected by means of a link 129 with one arm of a rock-lever 130 which is fulcrumed at 131 on the main frame and is connected by means of a link 132 with a peripheral lug on the cam 69, previously referred to, such cam in this connection operating, in effect, as a crank arm. The bar 107 is connected by means of a link 133 with the arm 134 of a crank lever which is fulcrumed at 135 on the lever 130. The other arm of this crank lever is provided with a roll 136 which runs in a fixed cam race 137 on the side of the main frame, said race being of such contour that during the oscillation of the rock-lever 130 to effect the vertical reciprocations of the driving bar, the crank lever is actuated to impart the requisite reciprocations to the bar 107 and the slide members 110. (See Fig. 3.)

By mechanism of the general construction illustrated in patent No. 578,907 aforesaid, the wire is intermittently fed to an anvil 138 which is periodically reciprocative into and from the path of the slide 110 in such manner that in the initial downward movement of the slide its depending jaws bear upon a section of wire and bend it over the anvil to form a staple, S, which is received between the grooved faces of the jaws, as seen in Fig. 18. In the continued descent of the slide the staple is caused to straddle the underlying tuft (T) which is positioned in the notched members 85 as previously explained; and the descending roll 118, bearing against the cam bar 119, operates the cam arm to force the opposing member 110 inward in a manner to bend the legs of the confined staple toward each other and partially beneath the tuft, as seen in Fig. 19, at or about which juncture the jaws of the slide impinge yieldingly against the brush block, as usual. Thereupon the bar 127 is forced downward, by its link and lever connections with the cam 69, in a manner to

impinge against the staple and drive it into the hole of the brush block. The staple in its descent doubles the wisp upon itself and carries it into the hole, the tuft being therein compressed and held by the staple, the legs 70 whereof converge into and are firmly and reliably held in the brush block, as seen in Fig. 21. In the descent of the staple the spring supporting fingers 87 yield to the downward pressure upon the tuft as above 75 mentioned.

A tuft guide casing 139 of known construction is mounted to swing in a vertical plane toward and from the brush block in timely relation to the vertical reciprocations of the tuft slide, which casing is operative not only to guide the individual tufts to the brush block, but also, by its end toes 140, to push out of the way of the entering tuft the previously inserted tuft irrespective of the 80 direction of movement, to the right or the left, of the brush block below the tuft inserting element. A feature of my invention resides in the provision of simple and efficient mechanism for effecting the periodic operation of the guide casing. See Figs. 1, 22, 23 and 24. As illustrated this casing overhangs the path of the brush block and is supported by a laterally extending rock-stud 141 having its bearing in a bracket 142 on the main frame. Fast on this stud is a gear sector 143 in mesh with a gear wheel 144 loose on a stud-shaft 145 extending from the frame, and secured to the gear is a rock-lever 146 that is fulcrumed on the stud. The outer ends of the respective arms of the lever are pivotally connected by links 147 to the lower ends of a pair of parallel slide bars 148 supported in a vertical guide structure 149 on the frame. These bars are respectively provided on their inner faces, intermediate their ends, with oppositely-disposed notches 150, and the relation of the parts is such that when the casing is in vertical position, centrally of the tuft-inserting slide, the bars 148 are in their lowermost position and the notches are directly opposite to each other, as seen in Fig. 22. Into either of these notches is adapted to be entered a laterally-projecting stud 151 on a pendulous bar 152 which is hung at its upper end from a stud 153 vertically reciprocative in a guide slot 154 formed in an upper extension 155 of the guide structure 149. On this stud is a link 156 which is connected with a crank arm 157 (Fig. 1) fast on the pivot stud 131 of the rock-lever 130, in such manner, as will presently be explained, that during the operation of the lever timely vertical reciprocation is imparted to the bar 152. Hence, if the stud 151 be engaged with the notch 150 of either of the bars 148 when the bars are in their lowermost position, the engaged bar and that end of the rock-lever 146 linked thereto will be raised in the upward stroke 100 105 110 115 120 125 130

- of the link 147, thereby partially rotating the gear wheel 144. The motion of this wheel will, of course, be reversely transmitted to the sector 143 and the guide casing 139 in a manner to swing the latter to the right or to the left of the vertical according to which bar 148 is elevated. The other bar 148 will of course be idly moved in the opposite direction.
- 10 The pedulous bar 152 loosely enters the recessed face of a horizontal slide 158 which is fitted to a transverse guide way 159 in the structure 149, whereby the reciprocation of the slide will swing the bar 152 back and forth to position the stud in the notch of either bar 148 as desired. The slide 158 is connected by means of a link 160 with the up-standing arm 161 (Fig. 1) of a lever which is suitably fulcrumed on the main frame. The other arm 162 of this lever bears a roll 163 which is yieldingly held in the path of a pair of spaced segmental cams 164 on the gear wheel 21 by means of a spring 165 that is secured to the arm 161 and to the main frame. The cams 164 are so formed and positioned on the wheel 21 that at periodic intervals in the rotation of the latter the lever is shifted to effect the requisite movements of the slide 158.
- 20 During the vertical reciprocation of the tuft slide the casing 139 is in vertical position and the stud 151 is engaged with the notch of one of the bars 148, the co-operative relation of the parts being such that the casing is temporarily locked. Upon the return of the slide to its uppermost position, the bar 148 is raised, thereby effecting the upward swing of the tuft casing, either to the right or to the left as required by the direction of travel of the brush block being filled. The upward movement of the casing clears it from the fibres of the tuft last inserted in the block and allows the free movement of the work either longitudinally or transversely, as the case may be, to bring the next adjacent hole in the block to the filling position.
- 30 As seen in Fig. 1, the connection previously mentioned between the link 156 and the crank arm 157 comprises a transversely perforated head 166 rotatably mounted on the crank-arm. The link extends slidably through and above the perforation of the head and is provided above and below the head with collars 167, 168, respectively, which are spaced apart to afford sufficient lost motion between them and the head to ensure the timely dwell of the tuft casing in its vertical and inclined positions in relation to the brush block. The collars are preferably adjustably secured to the link by means of set-screws 169, not only to facilitate their normal setting, but also to permit the independent adjustment of the upper collar to meet the requirements of tufts of different
- lengths. The collars are also preferably provided with cushioning springs 170. A retracting spring 171 secured to the upper end of the link 156 and to the main frame tends to steady and resiliently support the link 70 during its operation by the crank arm 157.
- 40 The co-operative arrangement of the various mechanisms hereinbefore described is such that when the wisp of fibre is carried under the tuft inserting mechanism by the fibre gathering bar the wisp is immediately transferred into the hooks 85, and, during the period of the downward motion of the tuft inserting devices, the fibre gatherer returns to the magazine for another supply of fibre; thus ensuring increased speed of operation and correspondingly increased production as compared with former machines wherein a dwell of the tuft inserting mechanism was necessary during the period of the transfer of fibre from the magazine to the inserting mechanism.
- 50 The operation of the machine may be summarized as follows:
- 55 The brush block is mounted on the block supporting table and the various positions of the table to present the block progressively to the actions of the drill and the tuft inserting and fastening devices are effected through the connections between the table and the intermittently rotating pattern cams 9, as usual. At the outset the table is positioned to present the forward end of the block beneath the drill, and the sleeved cam 30 is coupled to the continuously driven pulley 4 on the shaft 3 by manual actuation of the handle 580, said cam thus turning concurrently with the pulley. The partial turning of the handle 580 pushes the toggle outward against the action of the spring 51 in a manner to partially turn the rocker shaft 45 and effect the release of the brake from the brake drum 33. This done the cam 30 during its rotation actuates the lever 28 in a manner to oscillate the pawl-bearing lever 26 and effect by its pawl the uniform intermittent rotation of the associated ratchet and gear wheels, which motion is transmitted to the gear wheel 21 and to the shaft 7 and its pattern wheels, as previously described.
- 60 The cam 30 is coupled to the pulley 4 and the operation of the pattern wheel is continued until the brush has been completed, whereupon the laterally projecting stud 690 of the gear wheel 21 impinges against the cam head of the arm 670 and effects the release of the toggle, thus uncoupling the cam 30 from the pulley 4, and at the same time applying the brake to the drum 33 in a manner to prevent the cam 30 from drifting beyond the proper stopping point.
- 65 During the progressive operation of the block supporting table through the agency of the pattern wheels, or at predetermined

intervals of time during such operation, the cam 700 on the gear wheel 21 engages the roll of the crank lever 691 and effects a partial turn of the rocker cam 400, thereby 5 moving the roll 470 into the path of the clutch lever 340 and effecting the engagement of the latter with the clutch head 360 and also coincidentally releasing the brake members from the drum 330 which is keyed 10 to the shaft 3. Hence the shaft 3, on which are mounted the cam elements for operating the boring, the fibre gathering and the tuft inserting and fastening mechanisms, is rotated to effect the operation of the respective mechanisms.

As previously described the velocity of the shaft 7 and its pattern wheels are accelerated by the supplementary transmission gearing, during the inoperative interval of 20 the boring and filling mechanisms necessitated by gaps in the brush pattern or by jumps from one block to another, the periods of operation of such gearing being controlled through the agency of one or more 25 cams 860 on the gear wheel 21.

It is to be understood that my invention is not limited to the particular constructions herein disclosed, as the mechanisms may be modified in various respects within the principle of the invention and the scope of the appended claims.

I claim—

1. In a brush machine, the combination with a shaft and a driving element rotatable independently of the shaft, of block-boring, fibre-gathering and tuft-inserting mechanisms, each of said mechanisms including an actuating element therefor fast on said shaft, a block support, pattern devices operative to control the various positions of the block support in relation to the said mechanisms, said devices including a pattern wheel and a shaft therefor, a cam element loosely mounted on the first-named shaft, and means, including a driven member on said second-named shaft, actuated by said cam element for rotating the second-named shaft and the pattern wheel, a clutch connection between said driving and cam elements, manually operable means for actuating said connection to couple the driving and cam elements, said means including a locking element for permitting the maintenance of the members of the clutch device in engaged relation, means, including a projection on said driven member, operable at a predetermined point to actuate the said locking element and effect the release of the said clutch connection, a second clutch connection between said cam element and the first-named shaft, and means, including a projection on said driven member, operative to effect at predetermined intervals the engagement and the release of the second clutch connection.

2. In a brush machine, the combination with a shaft and a driving element rotatable independently of the shaft, of block-boring, fibre-gathering and tuft-inserting mechanisms, each of said mechanisms including an actuating element therefor fast on said shaft, a block support, pattern devices operative to control the various positions of the block support in relation to the said mechanisms, said devices including a rotary pattern wheel, a cam element loosely mounted on the shaft, and means actuated by said cam element for rotating the pattern wheel, a clutch connection between said driving and cam elements, manually operable means for actuating said connection to couple the driving and cam elements, said means including a locking element for permitting the maintenance of the members of the clutch device in engaged relation, means operable at a predetermined point during the rotation of the pattern wheel to actuate the said locking element and effect the release of the said clutch connection, a second clutch connection between said cam element and the shaft, means operative during the rotation of the pattern wheel to effect at predetermined intervals the engagement and the release of the said second clutch connection, and means to accelerate the speed of the said pattern wheel when the said second clutch connection is released.

3. In a brush machine, the combination with a shaft and a driving element rotatable independently of the shaft, of block-boring, fibre-gathering and tuft-inserting mechanisms, each of said mechanisms including an actuating element therefor fast on said shaft, a block support, pattern devices operative to control the various positions of the block support in relation to the said mechanisms, said devices including a rotary pattern wheel, a cam element loosely mounted on said shaft, and means actuated by said cam element for intermittently rotating said pattern wheel, a clutch connection between said driving and cam elements, manually operable means for actuating said connection to couple the driving and cam elements, means operative at a predetermined point during the rotation of the pattern wheel to release the clutch connection between the driving and cam elements, a second clutch connection between said cam element and said shaft, means operative during the rotation of the pattern wheel to effect at predetermined intervals the engagement and the release of the said second clutch connection, and means for continuously rotating the said pattern wheel at an accelerated speed when the said second clutch connection is released.

4. In a brush machine, the combination with a shaft and a driving element rotatable independently of the shaft, of block-

boring, fibre-gathering and tuft-inserting mechanisms, each of said mechanisms including a cam fast on said shaft, a block support, pattern devices operative to control the various positions of the block support in relation to the said mechanisms, said devices comprising a rotary pattern wheel, a cam element loosely mounted on said shaft and provided with a brake-drum, transmitting means between the said cam element and the pattern wheel, a clutch connection between the driving element and the brake-drum, brake members co-operating with said drum, manually operable means for releasing the brake members from the drum and engaging the clutch connection between the driving and brake members, means operative at a predetermined point during the rotation of the pattern wheel to apply the brake members to the drum and at the same time release the clutch connection between the driving and cam elements, a second brake drum fast on the shaft, brake members co-operating with said second brake drum, a clutch connection between said cam element and the second brake drum, and means operative at predetermined intervals during the rotation of the pattern wheel to effect the engagement of the brake members with, and the release of the clutch connection from said second brake drum.

5. In a brush machine, the combination with a shaft and a driving element rotatable independently of the shaft, of block-boring, fibre-gathering and tuft-inserting mechanisms, each of said mechanisms including a cam fast on said shaft, a block support, pattern devices operative to control the various positions of the block support in relation to the said mechanisms, said devices comprising a rotary pattern wheel, a cam element loosely mounted on said shaft and provided with a brake-drum, transmitting means between the said cam element and the pattern wheel, a clutch connection between the driving element and the brake-drum, brake members co-operating with said drum, manually operable means for releasing the brake members from the drum and engaging the clutch connection between the driving and brake members, means operative at a predetermined point during the rotation of the pattern wheel to apply the brake members to the drum and at the same time release the clutch connection between the driving and cam elements, a second brake drum fast on the shaft, brake members co-operating with said second brake drum, a clutch connection between said cam element and the second brake drum, and means operative at predetermined intervals during the rotation of the pattern wheel to effect the engagement of the brake members with, and the release of the clutch connection from said second brake drum.

40. the said mechanisms, said devices comprising a rotary pattern wheel, a cam element loosely mounted on said shaft and provided with a brake-drum, transmitting means between the said cam element and the pattern wheel, a clutch connection between the driving element and the brake-drum, brake members co-operating with said drum, manually operable means for releasing the brake members from the drum and engaging the clutch connection between the driving and brake members, means operative at a predetermined point during the rotation of the pattern wheel to apply the brake members to the drum and at the same time release the clutch connection between the driving and cam elements, a second brake drum fast on the shaft, brake members co-operating with said second brake drum, a clutch connection between said cam element and the second brake drum, and means operative at predetermined intervals during the rotation of the pattern wheel to effect the engagement of the brake members with, and the release of the clutch connection from said second brake drum, and means to accelerate the speed of the said pattern wheel.

when the brake member is engaged with, and the clutch connection is released from said second brake drum.

6. In a brush machine, in combination with a shaft and a driving element rotatable independently of the shaft, of block-boring, fibre-gathering and tuft-inserting mechanisms, each of said mechanisms including a cam fast on said shaft, a block support, pattern devices operative to control the various positions of the block support in relation to the said mechanisms, said devices including a rotary pattern wheel, gearing connected therewith, a cam element loosely mounted on the said shaft, and transmitting devices between the cam and the gearing for effecting the intermittent rotation of the pattern wheel, a clutch connection between said driving and cam elements, manually operable means for actuating said connection to couple the driving and cam elements, means operative at a predetermined point during the rotation of the pattern wheel to release the said clutch connection, a clutch connection between said cam element and the shaft, means operative during the rotation of the pattern wheel to effect at predetermined intervals the engagement and the release of the clutch connection between the said cam element and the shaft, continuously rotating supplemental gearing which is connected with the pattern wheel, and means whereby the supplemental gearing is moved into and out of mesh with the pattern wheel gearing at predetermined intervals during the rotation of the pattern wheel so as to accelerate the speed of said pattern wheel when the clutch connection between the cam element and the shaft is released.

7. In a brush machine, the combination with a shaft and a driving element rotatable independently of the shaft, of block-boring, fibre-gathering and tuft-inserting mechanisms, each of said mechanisms including an actuating element therefor fast on said shaft, a block-support, pattern devices operative to control the various positions of the block support in relation to the said mechanisms, said devices including a rotary pattern wheel, a cam element loosely mounted on the shaft, and means actuated by said cam element for rotating the pattern wheel, a clutch connection between the said driving and cam elements, manually operable means for actuating said connection to couple the driving and cam elements, said means including a toggle lever having a stop on one leg thereof, a cam lever operable to engage said stop and throw out the toggle lever, a handle rod, connections between said rod and the cam lever, and a locking lever having spaced abutments which co-act with the cam lever and having also an engaging portion for the said stop when the toggle lever is thrown out, means operable at a predetermined point during the

rotation of the pattern wheel to actuate the said cam lever to effect the disengagement of the locking lever from the said stop and thus effect the release of the said clutch connection, a second clutch connection between the said cam element and the shaft, and means operative during the rotation of the

pattern wheel to effect at predetermined intervals the engagement and the release of the second clutch connection.

Signed at Frederick, in the county of Frederick and State of Maryland this 13th day of November A. D. 1923.

WILLIAM D. LIPPS.
